(57) **CLAIM**

The ornamental design of a loudspeaker, as shown and described.

DESCRIPTION

FIG. 1 is a perspective view of a loudspeaker illustrating our new design;

FIG. 2 is a front view of the design of FIG. 1;

FIG. 3 is a rear view of the design of FIG. 1;

FIG. 4 is a side view of the design of FIG. 1;

FIG. 5 is an opposite side view of the design of FIG. 1;

FIG. 6 is a top view of the design of FIG. 1;

FIG. 7 is a bottom view of the design of FIG. 1;

FIG. 8 is a perspective view of an alternative embodiment of a loudspeaker illustrating our new design;

FIG. 9 is a front view of the design of FIG. 8;

FIG. 10 is a rear view of the design of FIG. 8;

FIG. 11 is a side view of the design of FIG. 8;

FIG. 12 is an opposite side view of the design of FIG. 8;

FIG. 13 is a top view of the design of FIG. 8;

FIG. 14 is a bottom view of the design of FIG. 8;

FIG. 15 is a perspective view of an alternative embodiment of a loudspeaker illustrating our new design;

FIG. 16 is a front view of the design of FIG. 15;

FIG. 17 is a rear view of the design of FIG. 15;

FIG. 18 is a side view of the design of FIG. 15;

FIG. 19 is an opposite side view of the design of FIG. 15;

FIG. 20 is a top view of the design of FIG. 15; and,

FIG. 21 is a bottom view of the design of FIG. 15.

The broken lines, if any, represent portions of the structure that form no part of the claim.
